UNITED STATES PATENT OFFICE

LOUIS O. SUTTON, OF WILMINGTON, DELAWARE.

GAME APPARATUS.

994,963.

Specification of Letters Patent. Patented June 13, 1911.

Application filed December 16, 1910. Serial No. 597,601.

To all whom it may concern:

Be it known that I, LOUIS O. SUTTON, a citizen of the United States, residing at Wilmington, in the county of Newcastle and 5 State of Delaware, have invented certain new and useful Improvements in Game Apparatus, of which the following is a specification.

My invention relates to improvements in 10 game apparatus, an object of the invention being to provide an improved game table designed especially for playing the game of baseball, and which will automatically record on the board by means of electric lights, the 15 representation of a base runner moving along the base lines, and at the several bases.

A further object is to provide an improved 20 table indicating thereon the representation of a baseball field with the base lines transparent, and electric lights under the base lines and at the bases, said lights included in circuits which are closed by the movement of cue balls in accordance with the movement of the latter.

25 A further object is to provide a game board or table having a cushion against which cue balls are adapted to be driven by means of the ordinary cue, and provide electric contacts in circuit with electric lights, 30 said contacts moved together by the ball as it is deflected from the cushion, so as to cause the illumination of certain of said lights.

35 A further object is to provide a game apparatus of this character in which openings are provided in the board or table through which the cue balls pass when said balls fail to engage the contacts above referred to, and in which position said balls record outs in 40 the game of baseball, and provide below said openings, alleys joining a common alley for the care of the balls passing through said openings, said openings being located on the field at the positions ordinarily occupied by 45 the players.

A further object is to provide an improved arrangement of ballways, electric contacts, metal balls, gates, and electro-magnets controlling the passage of the balls down the 50 ballways in accordance with the contact closed by the cue ball, giving to the representation of the diamond or base paths the appearance of a runner moving along the base lines from base to base, such impression being caused by the regular and successive

lighting and extinguishing of the lights in the path.

A further object is to provide improved 60 means for releasing into the several ballways a single ball at a time, and permitting said ball to move in the ballway a distance equal to the distance around the base paths in accordance with the particular contact closed by the cue ball, and permitting balls which 65 illuminate the lights at any of the bases to move in a proportionate distance on the base lines, such as a player would ordinarily move in an ordinary game of baseball in response to the kind of hit recorded by the closed contact. 70

A further object is to provide improved 75 ballways for metal balls, said metal balls adapted to close electric circuits as they move along the ballways, causing the successive illumination of lights in the base lines, and provide improved means for returning the balls to their hopper or supply chamber.

80 A further object is to provide an improved arrangement of electric circuits whereby all of the several operations are automatically performed to release the several circuit closing balls, and control their movement down their several ballways in accordance with the contacts closed by the cue balls, and automatically close the electric circuits of the 85 lights in the base path and at the bases.

With these and other objects in view, the 90 invention consists in certain novel features of construction and combinations and arrangements of parts, as will be more fully hereinafter described and pointed out in the claims.

In the accompanying drawings: Figure 1, 95 is a plan view illustrating my improvements. Fig. 2, is a view in longitudinal section. Fig. 3, is a view in cross section. Fig. 4, is an inverted longitudinal section on the line 4-4 of Fig. 2. Fig. 5, is a sectional plan view of the ballways. Fig. 6, is a view 100 partly in longitudinal section and partly in elevation on the line 6-6 of Fig. 1. Fig. 7, is a sectional plan view on the line 7-7 of Fig. 6. Fig. 8, is an enlarged fragmentary plan view of a portion of the 105 ballways showing one of the electro-magnetic gates. Fig. 9, is a view in cross section through Fig. 8. Fig. 10, is a longitudinal section illustrating on an enlarged scale one of the contacts closed by the cue balls. 110

Fig. 11, is an enlarged sectional view at right angles to Fig. 10. Fig. 12, is a diagram showing the arrangement of electric circuits between the several contacts and the electro-magnetic gates. Fig. 13, is a diagram showing the electric circuits between the several contacts in the ballways and the lights in the base lines, and Fig. 14, shows an ordinary cue and cue balls with which 10 the game is played.

The game apparatus comprises a box-like body having a bottom 1, sides 2, 2, ends 3, and a top 4, the top 4 constituting the field which is located a distance below the upper 15 edges of the sides and ends to confine the cue balls on the field during the playing of the game. The body is preferably supported on suitable legs 5, and is of approximately the same size as an ordinary billiard 20 or pool table. On the top or table 4 transparent strips 6 are inserted representing the base lines of ordinary baseball diamonds, which connect transparent squares 7 which I shall term "bases." Beneath each base, 25 and beneath the transparent strips 6, are electric lights 8, and for convenience of description I shall hereinafter refer to these lights as "base line" lights and "base" lights.

30 At one end of the table is a deflecting cushion 9 which is of general heart shape cut under as shown more particularly in Fig. 2, and adapted to be struck by an ordinary cue ball 10^a when operated by an ordinary cue 11^a illustrated in Fig. 14.

Back of the representation of the diamond, and at points which would ordinarily be occupied by players on an ordinary baseball field, openings 10 are provided in the 40 top 4, blocks 11 being located back of said openings to serve as abutments, and the walls of said openings removed from said blocks, being beveled or inclined to more effectually direct the cue balls into the openings. Below the several openings 10, channels or passages 12 are provided which incline downwardly to a common passage 13, and the latter discharges through an opening 14, so that any cue ball which may fall 45 through any of said openings will pass into a receptacle 15 provided for their reception outside of the table.

Below the top or field 4, but located within the box-like body, is an inclined table 16, 55 which comprises a hopper 17 at its upper end with which a series of longitudinal ballways communicate. These ballways I have given different reference characters for convenience of description. There are 60 four main ballways which I number 18, 19, 20, and 21, respectively which extend from the hopper or chamber 17 throughout the length of the table and discharge into a transverse chute 22. In addition to 65 these ballways, a fifth ballway 23 is pro-

vided which communicates with the first ballway 18 at a point removed from the chamber or hopper by means of a short branch ballway 24, and this ballway 23 also extends to and communicates with the transverse chute 22. 70

The chamber or hopper 17 is adapted to contain metal balls 25 which are adapted to move down the several ballways into the chute 22, and from the latter directed 75 through a passage 26 to a conveyer 27. This conveyer 27 is constructed to elevate the metal balls back into the chamber or hopper 17, and may be operated by any suitable mechanism (not shown). 80

The table 16 is composed of non-conducting material, and its ballways are of general V-shape containing metal contact plates 28 in its opposite faces spaced apart, insulated from each other, and yet connected in electric circuits with the several lights 8 under the base line 6 and bases 7. A diagram of these electric circuits is shown in Fig. 13 85 illustrating the several independent circuit wires 29 connecting the lights 8 with the contact plates 28, and all of said circuits are electrically connected with a supply main 30, and in this diagram the bases corresponding to the bases of the field are indicated in line, and not as they actually appear on the field. 90

At the entrance or upper end of the ballways 18, 19, 20, and 21, where they communicate with the hopper or chamber 17, electro-magnetic gates 31, 32, 33, and 34 respectively are located. In the ballway 18 at a point distant from the hopper one-fourth of the length of the ballway, and at the point of communication between the ballway 18, and the branch ballway 24, two of such electro-magnetic gates 35 and 36 are provided, the gate 35 controlling the direct passage down the ballway 18, and the gate 36 controlling the passage down the branch ballway 24. At a point half way down ballway 19, is an electro-magnetic gate 37, and at points three-quarters of the way down ballways 18 and 20 are electro-magnetic gates 38 and 39 respectively. Each of these electro-magnetic gates as I term them comprises a bracket 40 of general bowed form supporting an electro-magnet, the core of which extends through the bracket 40, into the path of a metal ball 25 far enough to hold the ball against movement down the ballway, hence these gates are adapted to hold the balls in positions on the contact plates 28 in the several ballways to close the electric circuits which illuminate the lights below the bases. For example, gates 35 and 36 hold a ball in position to close the contact and light the first base light. Gate 37 holds a ball in position to light the second base light, and gates 38 and 39 hold a ball in position to light the third base light. 125

These several electro-magnetic gates or electro-magnets, which constitute the operative element of the gates, are controlled by electric-circuits indicated diagrammatically in

5 Fig. 12, and these electric circuits are adapted to be closed by the weight of the cue ball to raise the armature or gate as will hereinafter appear.

In the sides 2 and ends 3 of the box-like 10 body which project above the top or field 4, recesses or grooves 41 are provided for the reception and passage of the cue balls, and said passages incline to a pocket 42 at one end of the table, so that these balls which

15 do not enter the openings 10 are returned for further use. At the entrance to these grooves 41, vertically movable platforms are located, and are given separate reference characters for clearness of description.

20 The sides 2 at points in line with the first and third base lines of the diamond illustrated by the transparent sections 6, are curved or projected inwardly as shown at 42^a, so that balls which do not come inside

25 of the lines 6, in other words, foul balls are deflected back into the field. Between these inwardly projecting portions 42^a, and the playing end of the field, and at both sides of the table, are two platforms and at the

30 player end of the table are three of these platforms making seven in all. The first two platforms or those adjacent the representation of a diamond, I give reference characters 43 and 44 respectively, and these

35 platforms are what I term "one base hit" platforms. The adjacent platforms 45 and 46 which extend from the ends of platforms 43 to the end of the field, I term "two base hit" platforms. The outside platforms 47

40 and 48 at the end of the table I term "three base hit" platforms, and the central platform 49 at the end of the table I term "home run" platform. These platforms 43, 44, 45, 46, 47, 48, and 49 are constructed precisely

45 alike. They each are supported at their ends upon pins 50, around which coiled springs 51 are provided normally spacing contacts 52 and 53 apart. As the cue ball in order to pass into the grooves 41 must

50 pass over one of these platforms, the weight of the ball will be sufficient to move the contacts 52 and 53 together to close the electric circuit in which said contacts are included to

55 operate the several electro-magnetic gates as will be explained.

In playing the game, the cue is utilized to direct the ball against the cushion 9, and owing to the peculiar shape of the latter considerable science is necessary to direct

60 the ball. The object, of course, is to direct the ball over one of the "base hit" platforms and prevent it from passing into any of the openings 10. When the ball passes into the openings 10, the scorer records one

65 out. When it passes over a "base hit" plat-

form, a metal ball 25 will be released so that the lights 8 will be illuminated in succession and give the appearance of a base runner moving along the base lines from one base to another, and this operation of the 70 metal balls is controlled by the electro-magnetic gates through the medium of electric circuits shown in Fig. 12, and which will now be described.

In the following description, it is to be 75 understood that referring to the several platforms, that this reference includes the electric contacts which form a part of said platforms.

As the magnets 37, 38, and 39 always operate simultaneously with any one of the magnets 31, 32, 33, and 34, and with either magnet 35 or 36, the said magnets 37, 38 and 39 are included in a multiple arc circuit 54, which includes magnet 35, and magnet 31, 80 85 and by means of branch wires 55 includes magnet 36. The wires of circuit 54 are connected by wires 56 and 57 with the "first base hit" platforms 44 and 43 respectively, and these circuits are connected by branch 90 wires 58 with the line wires 59. Included in the circuits of the wires 56, 57, and 54, is the magnet 31 which controls the release of metal balls from hopper 17 into the ballway 18. The "two base hit" platforms 45 95 and 46 are connected by wires 60 with wires 61, which connect with the branch wires 55, and include in the electric circuit the electro-magnet 32 which controls the passage of balls from the hopper 17 into the ballway 100 19. The "three base hit" platforms 47 and 48 are connected by wires 62 with the branch wires 55, and include in the electric circuit the magnet 33 which controls the passage of balls from the hopper 17 to the ballway 20. 105 The "home run" platform 49 is connected by wires 63 with the branch wires 55, and includes in the electric circuit, the magnet 34 which latter controls the passage of balls from hopper 17 into ballway 21. Each of 110 these circuit wires 60, 62, and 63, like wires 56, are connected by branch wires 58 with the line wires 59, and all of these several circuits are normally opened and held open by means of the springs 51 of the several platforms. 115

In playing the game, a cue ball is placed upon the field, and is struck by the cue to strike the ball against the cushion 9. The object, of course, is to English the ball in a 120 desired way so as to make it escape the several openings 10, and pass over at least one of the platforms, preferably those highest in value, and due to the location of the openings 10, the difficulty of directing the ball 125 over the higher value platforms is proportionately increased, for example, it being easier to direct the ball over the "one base hit" platforms 43 and 44, and then over the "two base hit" platforms 45 and 46, etc. 130

We will assume that when the cue ball is struck, it is deflected backward into fair ground escaping the projections 42^a, and passes over the platform 43, making a base 5 hit to right field. As soon as the ball depresses the platform 43, the electric circuit will be closed so as to momentarily energize magnets 31, 35, 37, 38, and 39, and a metal ball 25 will therefore be released down ball- 10 way 18, but the core of magnet 35 will have descended before the ball reaches that point, so that the ball will be stopped by the core of the magnet, or by the electromagnetic gate as this is referred to. As the metal ball 15 passes down the ballway 18, it will successively close the electric circuits which include the contact plates 28, and cause the lights 8 under the transparent strip 6 between the home plate and the first base to be 20 successively lighted, and as long as the ball is held by the magnet 35, it will maintain illuminated the light under the first base plate 7. We will suppose that the next cue ball which is shot against cushion 9 is deflected, so that it passes into one of the openings 10. This will record one out and the base runner on first base will not advance. 25 We will assume that the next cue ball which strikes cushion 9, passes over "first base hit" 30 platform 44, which will be a single to left field. When this happens, platform 44 will close the electric circuit between the wires 35 56, causing magnets 31 and 35 to be energized as well as the magnets 37, 38, and 39 which are always energized at every operation of any platform. The metal ball 25, 40 which was held by magnet 35, will roll down ballway 18 as far as the magnet 38, and the lights under the base paths between the first and second, and second and third will be successively lighted, which will give the appearance of a base runner running from first to third base, and the third base light will remain lighted. At the same time a second 45 ball will enter ballway 18, and roll down to the magnet 35, causing the lights under the base path between home plate and first base to be successively illuminated, giving the appearance of a runner going down to first 50 base, and the first base light will remain lighted. The field will then show a man on first and a man on third base. We will now suppose that the next cue ball which strikes cushion 9 passes over the home run platform 49. When this occurs, the circuit will be closed through the wires 63 energizing magnet 34, and magnets 36, 37, 38, and 39. It will therefore be noted that the magnet 35 is not energized, but magnet 36 is, which 55 permits the ball to roll through the ballway 23 throughout the length of the table, and the ball against magnet 38 to roll down ballway 18 to the end of the table. At the same time, the ball which is permitted to enter 60 ballway 21 by reason of energizing magnet 65

34 will pass throughout the entire length of the ballway 21. This movement of the balls will cause the successive illumination of the lights below the base paths, so that it will give the general impression of the man on 70 third base running home, the man on first base running around home, and the batter encircling the base paths. The scorer will, of course, record three runs. If the next two cue balls enter holes 10, the inning will 75 be over for that player. The next player then uses these cue balls which are delivered into the receptacle 15. Cue balls which do not pass through the openings 10 are guided into the pocket 42, and are used over and 80 over again. The several metal balls as they pass throughout the table, enter the chute 22 and are directed back by the passage 26 to the head of the table into the path of movement of a conveyer 27, which latter is operated by any suitable mechanism (not shown) to convey the metal balls upward 85 into the chamber or hopper 17 for reuse.

In playing this game, the electro-magnetic gates are so arranged that the normal play 90 on a baseball diamond as the result of base hits is recorded electrically on the representation of the baseball diamond. In other words, if a man is on first base, a single will place him on third. If he is on first base, 95 a double, triple, or home run will carry him all the way home ahead of the batter who will stop on the base paths in accordance with the hit he makes. If a runner is on second base, a single will bring him home. 100 The auxiliary ballway 23 with its electromagnetic gate 36 is provided so that a base runner on first base will be driven all the way home ahead of a batter making more than a single for in such event as above explained in connection with the several circuits, magnet 36 will be energized to allow a ball to pass down the ballway 23, while the magnet 35 prevents the ball from passing down ballway 18. Any ball which strikes 105 the side lines before passing over first or third base is a foul. If such ball eventually falls into the one of the pockets 10, it is a foul out. If the ball stops on the field, it would simply record a strike, and three of 110 such strikes would be out. A great many combinations of plays may be made on the board, and rules laid down for certain positions in which the ball stops. If such positions entitle the player to hits according to 115 the rules, the several platforms may be manually depressed so as to properly register on the board, but the invention is of course not limited to the particular rules employed.

120 Various slight changes might be made in the general form and arrangement of parts described without departing from my invention, and hence I do not limit myself to the precise details set forth, but consider myself 125 130

at liberty to make such changes and alterations as fairly fall within the spirit and scope of the appended claims.

Having thus described my invention, what I claim as new and desire to secure by Letters Patent is:

1. A game apparatus, comprising a field, transparent base lines on said field, lights below said base lines normally extinguished, and cue ball controlled means for successively illuminating the lights below the base lines and at the bases, substantially as described.

2. A game apparatus, comprising a field, transparent base lines on said field, lights below said base lines normally extinguished, a cushion on said field, a ball adapted to engage said cushion, and means operated by said ball successively illuminating the lights below the base lines and the bases, substantially as described.

3. In a game apparatus, the combination with a field, transparent base lines on said field, transparent bases at the ends of said base lines, and electric lights below said base lines and bases, of a cushion at one end of said field back of one of said bases, a cue ball adapted to be moved against said cushion, openings in said field for the reception of said ball, and electric contacts on said field adapted to be operated by said ball and controlling the illumination of said lights, substantially as described.

4. In a game apparatus, the combination with a field, transparent base lines on said field, transparent bases at the ends of said base lines, and electric lights below said base lines and bases, of a cushion at one end of said field back of one of said bases, a cue ball adapted to be moved against said cushion, openings in said field for the reception of said ball, means below said field controlling the illumination of said lights, and means on said field operated by said ball for controlling the operation of the first-mentioned means, substantially as described.

5. In a game apparatus, the combination with a field, transparent base lines on said field, transparent bases at the ends of said base lines, and electric lights below said base lines and bases, of a cushion at one end of said field back of one of said bases, a cue ball adapted to be moved against said cushion, openings in said field for the reception of said ball, means below said field controlling the illumination of said lights, and electric circuit-closing means on said field operated by said ball for controlling the operation of the first-mentioned means, substantially as described.

6. In a game apparatus, the combination with a field, transparent strips on said field indicating base lines, transparent pieces at the juncture of said base lines indicating bases, electric lights below said base lines

and bases, and an elastic cushion on said field back of one of said bases, of a cue ball adapted to engage said cushion and be deflected back over said field, said field having openings therein to receive said ball, passages below said openings, a common passage into which all of said first-mentioned passages empty, and electric means operated by said ball for illuminating certain of said lights under said base lines and bases, substantially as described.

7. In a game apparatus, the combination with a field, transparent strips on said field indicating base lines, transparent pieces at the juncture of said base lines indicating bases, electric lights below said base lines and bases, and an elastic cushion on said field back of one of said bases, of a cue ball adapted to engage said cushion and be deflected back over said field, said field having openings therein to receive said ball, passages below said openings, a common passage into which all of said first-mentioned passages empty, electric means below said field controlling the illumination of said lights, and electric means on said field operated by said ball for controlling the operation of the first-mentioned means, substantially as described.

8. In a game apparatus, the combination with a field, transparent strips on said field indicating base lines, transparent pieces at the juncture of said base lines indicating bases, electric lights below said base lines and bases, and an elastic cushion on said field back of one of said bases, of a cue ball adapted to engage said cushion and be deflected back over said field, said field having openings therein to receive said ball, passages below said openings, a common passage into which all of said first-mentioned passages empty, electric contacts, vertically movable platforms on said field depressed by said ball to close said electric contacts, and electric circuits in which said contacts are included controlling the operation of said first-mentioned means, substantially as described.

9. A game apparatus, comprising the representation of a baseball diamond, lights along the base lines and at the bases, means for controlling the illumination of said lights, said light controlling means comprising an inclined table having a plurality of ballways, a chamber at the upper end of said table, metal balls in said chamber, electro-magnetic gates controlling the passage of said metal balls into and through said ballways, cue ball operated electric contacts controlling the operation of said gates, and metal contacts in said ballways in electric circuit with said lights, substantially as described.

10. A game apparatus, comprising a field, transparent base lines on said field, lights below said base lines normally extinguished,

means for successively illuminating the lights below the base lines and at the bases, said light controlling means comprising an inclined table having a plurality of ball-
ways, a chamber at the upper end of said table, metal balls in said chamber, electro-
magnetic gates controlling the passage of said metal balls into and through said ball-
ways, cue ball operated electric contacts con-
trolling the operation of said gates, and

metal contacts in said ballways in electric circuit with said lights, substantially as described.

In testimony whereof I have signed my name to this specification in the presence of 15 two subscribing witnesses.
